UNITED STATES PATENT OFFICE.

CHARLES A. GRIFFITH, OF PRUDEN, TENNESSEE.

CAR-DUMPING APPARATUS.

1,108,575. Specification of Letters Patent. Patented Aug. 25, 1914.

Application filed March 16, 1911, Serial No. 614,819. Renewed April 6, 1914. Serial No. 830,088.

To all whom it may concern:

Be it known that I, CHARLES A. GRIFFITH, a citizen of the United States, residing at Pruden, in the county of Claiborne and State of Tennessee, have invented certain new and useful Improvements in Car-Dumping Apparatus, of which the following is a specification, reference being had therein to the accompanying drawing.

This invention relates to improvements in car dumping apparatus of the type in which the car is tilted to an angle such that the material within the car will slide out through an opening in the end.

More specifically, my invention relates to improvements in apparatus such as that disclosed in Patent No. 982,426 for mine car dumping apparatus, issued to me Jan. 24, 1911, and in my co-pending application for mine car dumping apparatus, filed Dec. 27, 1910, Serial No. 599,241.

My present invention has for its object to provide a dumping apparatus of this class having improved means for controlling the movement of a car including improved devices for gradually bringing the car to a rest.

Other objects will be apparent from the following specification.

In the accompanying drawings, which form a part of this specification, I have shown that form of mechanism which I now deem preferable. However, it will be obvious that certain changes and modifications

may be made within the spirit and scope of my invention.

Of the drawings, Figure 1 is a side elevation. Fig. 2 is a plan view. Fig. 3 is an end cross sectional elevation. Fig. 4 is an enlarged detail view of the segment and adjacent parts.

Referring to the drawings, 1 and 2 represent two substantially horizontal track sections positioned at different elevations. These track sections may be mounted upon any suitable framework, such as that shown in the drawings. Between these two track sections there is located a connecting section comprising two rails 3, 3. These rails

are preferably rectangular in cross section and are narrower than the treads of the ordinary track rails. Each of the rails 3, 3 is shaped to have one part 4 in substantial alinement with the upper main track section

5, another part 5 in substantial alinement with the lower main track section 2, and an

intermediate sharply inclined part 6 between the parts 4 and 5.

7 is a transverse shaft rotatably mounted in suitable bearings 8, 8 secured to the rails 3, 3, preferably on the inclined parts 6, 6. 9, 9 are horns rigidly secured to the shaft 7 at points adjacent and outside of the bearings 8, 8. These horns are adapted to swing with the shaft 7 about the axis thereof into and out of the paths of the wheels of a car on the track.

10 represents as a whole a quadrant or segment rotatably mounted upon the shaft 7, preferably near one end. In the drawings, for the sake of illustration, the segment is shown at the left-hand end, but this, of course, is not essential. The segment 10 preferably comprises two separate parts 11 and 12, each of which has a separate bearing 7 on the shaft. The parts 11 and 12 are connected in any desirable manner at their outer edges, there being a segmented recess formed between them. One of these parts, as for instance 11, is provided with an arched outer surface in which there is formed a circumferential extending groove 13, at the upper end of which there is a notch or pocket 14.

15 is an arm, forked at its outer end, and rigidly secured at its inner end to the shaft 7 between the bearings of the two segment parts 11 and 12. The arm is therefore in position to move within the recess between the segment parts.

16 is a rod pivotally connected at one end between the forks at the outer end of the arm 15, and slidably extending intermediate its ends through a yoke 17 which is pivotally mounted between the segment parts 11 and 12. A coil compression spring 18 surrounds the other end of the rod 16. This spring has a bearing at one end against the yoke 17 and is secured at its other end by means of nuts and washers to the rod 16.

The spring, therefore, tends to normally hold the arm 15 and the horns 9, 9 in the positions relative to the segment 10, which are indicated by the dotted lines in Fig. 1.

As indicated most clearly in Fig. 4, the movement of the arm 15 against the movement of the spring 18 may be positively limited by engagement with the boss 10 on the segment. A coil compression spring 15^b may be provided to relieve the shock of engagement. Similarly a compression spring

15^b may be provided to limit the movement

HOISTING APPARATUS

of the arm 15 in the other direction under the influence of the spring 18.

19 is a shaft parallel to the shaft 7 and rotatably mounted in bearings 20, 20, which are secured to the rails 3, 3.

21 is an operating lever provided with a handle at its upper end. This is secured to the shaft 19, preferably at the right-hand end.

10 The frame of the bearing 20 at the side of the apparatus on which is located the segment 10 is provided with a downward extension through which there is an aperture in alignment with the groove 13 of the segment. In this aperture there is slidably mounted a latch 22, which extends into the groove 13 and which is adapted to enter the pocket 14 when in alignment therewith. A bolt 23 connected with a compression coil 24 serves to hold the latch in the groove and to cause it to engage the notch at the proper time. A pin 25 is connected to the latch and this is adapted to be engaged by a hook 26 at the lower end of an arm 27 which is mounted upon the shaft 19.

28 is a brake wheel mounted on the shaft 7, preferably at the end opposite that on which the segment 10 is mounted.

29 is a brake band for the wheel 28. The upper end of this brake band may be secured directly to the shaft 19 as indicated. The lower end is connected to a yoke mounted between two arms 30, 30 on the shaft 19.

31 is a counter-weight connected with the operating lever 21 by means of a rope or cable 32 which passes over the sheave 33.

34 indicates a car in dumping position. Any desired type of car adapted for the purpose may be used. The end door may be opened either by hand or by any desired mechanical means. In the drawings, I have indicated two substantially horizontal bars 35 for engaging the door parts to hold them relatively elevated when the car is in dumping position. However, other means may be used, if preferred. 36 is a chute mounted beneath the rails 3, 3 for receiving the coal or other material as it slides from the car.

In operation when a loaded car enters the dumping apparatus it first engages the horns 9, 9, when they are in the upper positions, indicated by dotted lines in Fig. 1. On account of the momentum and weight of the car the horns are moved against the influence of the spring 18 to the positions shown in full lines in Fig. 1. This movement of the horns after being engaged by the car wheels may be resisted not only by the spring 18 but also by the friction of the brake band 29 against the wheel 28. The brake is held normally operative by the counter-weight 31, but the braking action may be either increased or diminished by the operator by means of the lever 21. The speeds with

65 which cars enter the apparatus will vary

and the weights of cars will vary, and it is therefore desirable to correspondingly vary the resistance which the cars must meet in being brought gradually to a rest. As the car approaches dumping position the end door is opened by the bars 35 and the contents of the car slide out into the chute 36. After the car has been emptied the operator by moving the lever 21 in the other direction may not only release the brake band 29 from the wheel 28 but may also withdraw the latch 22 from the notch 14 with which it is normally engaged. As soon as the latch is withdrawn from the notch, then the segment 10 is free to move and corresponding movement of the shaft 7 and the horns 9, 9 under the weight of the car is made possible. As soon as the horns have moved down far enough the car is automatically released and passes on to the lower main section 2. The upward movement of the segment 10 is limited by the engagement of the latch 22 with the lower end of the groove 13. As soon as the horns have been disengaged from the car wheels they are immediately returned to their normal positions relative to the segment 10 by means of the spring 18. At the same time they are farther moved upward by the segment 10 which returns to its normal position under the influence of gravity and carries with it the other parts with which it is connected.

It will be observed that by my invention I have provided a dumping apparatus which is very simple in construction and which may be controlled with a minimum of effort on the part of the operator. There is but a single operating lever, and this lever serves not only to regulate the resistance of the movement of the car in bringing it to a stop, but also to release the car after dumping. The cars are stopped with practically no shock and as a result there is less danger of derailment and there is less wear and tear on the cars themselves and on the apparatus as a whole.

What I claim is:

1. In an apparatus of the class described, the combination of a track, a movable element adapted to engage a car on the said track, a spring connected with the said element and adapted to resist its movement together with that of the car, a brake also connected with the said element, and also adapted to resist its movement together with that of the car, and means for regulating the resisting action of the said brake.

2. In an apparatus of the class described, the combination of a track, a pivotally mounted element arranged to move along lines extending from points in the path of a car on the track to points outside the said path in the general direction of movement of the car, a spring connected with the said

element for resisting its movement and the movement of the car, and a brake also connected with said element and also adapted for resisting its movement and the movement of the car.

3. In an apparatus of the class described, the combination of a track, a pivotally mounted element movable along lines extending from points in the path of a car on the track to points outside the said path in the general direction of movement of the car, a spring connected with the said element for resisting its movement and the movement of the car, and a reciprocable means supplementary to the said spring for also resisting the movement of the element and of the car.

4. In an apparatus of the class described, the combination of a track comprising a sharply inclined section, a movable element adapted to engage a car in dumping position on the said inclined section, means for first resisting and then stopping the movement of the said element in one direction together with that of the car, the said means comprising a spring connected with the element, and a resisting device supplementary to the said spring, also connected with the said element.

5. In an apparatus of the class described, the combination of a track comprising a sharply inclined section, a movable element adapted to engage a car in dumping position on the said inclined section, means for first resisting and then stopping the movement of the said element and of the car in one direction, the said means comprising a spring connected with the element, a brake also connected with the element, and means for regulating the resisting action of the brake.

6. In an apparatus of the class described, the combination of a track comprising a sharply inclined section, a reciprocable element adapted to engage a car in dumping position on the inclined section to first resist and then stop the movement thereof, the said element being movable along lines extending in the general direction of movement of the car from points in the path thereof to points outside the said path, and means for controlling the movement of the said element, the means comprising a spring for resisting the movement of the element, and a brake for also resisting the movement of the element.

7. In an apparatus of the class described, the combination of a track comprising a sharply inclined section, a reciprocable element adapted to engage a car in dumping position on the inclined section to first resist and then stop the movement thereof in one direction, the said element being movable along lines extending in the general direction of movement of the car from points in the path thereof to points outside of the said path, and means for controlling the

movement of the said element, the said means comprising a spring for resisting the movement of the element and a regulable means supplementary to the spring for also resisting the movement of the element.

8. In an apparatus of the class described, the combination of a track comprising an inclined section, an oscillatory element adapted to engage a car in dumping position on the inclined section, the said element being movable about its axis along lines extending from points in the path of the car to points outside the said path in the general direction of movement of the car, and means for controlling the said element to first resist and then stop the movement of the car, the said means comprising a spring connected with the element to resist its movement and a brake also connected with the said element to resist its movement.

9. In an apparatus of the class described, the combination of a track comprising an inclined section, an oscillatory element adapted to engage a car in dumping position on the inclined section, the said element being movable about its axis along lines extending from points in the path of the car to points outside the said path in the general direction of movement of the car, and means for controlling the said element to first resist and then stop the movement of the car, the said means comprising a spring connected with the element to resist its movement and a regulable means supplementary to the spring for also resisting its movement.

10. In an apparatus of the class described, the combination of a track comprising a sharply inclined section, a pivotally mounted element adapted to move about its axis along lines extending from points in the path of a car in dumping position on the inclined section to points outside the said path in the general direction of movement of the car, a spring connected with the said element for resisting its movement and the movement of the car, and a brake also connected with the said element, and also adapted for resisting its movement and the movement of the car.

11. In an apparatus of the class described, the combination of a track comprising a sharply inclined section, a pivotally mounted element movable along lines extending from points in the path of a car in dumping position on the said inclined section to points outside the said path in the general direction of movement of the car, a spring connected with the said element for resisting its movement and the movement of the car, and a regulable means supplementary to the said spring for also resisting the movement of the element and of the car.

12. In an apparatus of the class described, the combination of a track comprising a sharply inclined section, reciprocable elements adapted to engage the wheels of a

- car in dumping position on the said inclined track, means connected with the said reciprocable element for controlling it to resist and momentarily stop the movement of a car, the said means comprising a spring connected with the said element, and a regulable means supplementary to the spring also connected to the said element.
13. In an apparatus of the class described, the combination of a track comprising an inclined section, oscillatory elements arranged to engage the wheels of a car in dumping position on the said track, the said elements being movable about their axes to points outside the path of the said wheels, and means for controlling the said elements to resist and momentarily stop the movement of a car, the said means comprising a spring connected with the element, a brake also connected with the element, and means for regulating the action of the said brake.
14. In an apparatus of the class described, the combination of a track comprising an inclined section, an oscillatory shaft extending transversely of the said track, horns secured to the shaft and adapted to extend into the path of the wheels of a car on the said track, means connected with one part of the shaft for controlling its movement and the movement of the said horns, and a brake connected to another part of the said shaft.
15. In an apparatus of the class described, the combination of an inclined track, an oscillatory shaft extending transversely of the said track, horns secured to the shaft and adapted to extend into the path of the wheels of a car on the said track, controlling means connected with one part of the shaft, an additional controlling means connected to another part of the said shaft, the said additional means comprising a brake and a device for regulating the resisting action of said brake.
16. In an apparatus of the class described, the combination of an inclined track, an oscillatory shaft extending transversely of the track, horns on the shaft adapted to extend into the path of the car on the track, means secured to one part of the shaft for limiting its oscillatory movement, a latch for holding the said limiting means, a brake connected with another part of the said shaft, a second oscillatory shaft, means for operating it, means connected with the said second shaft for actuating the said brake when the second shaft is moved in one direction, and means connected with the second shaft for releasing the said latch when the shaft is moved in the other direction.
17. In an apparatus of the class described, the combination of an inclined track, an oscillatory shaft extending transversely of the track, horns on the shaft adapted to extend into the path of the wheels of a car
- on the track to control the movement thereof, means comprising a latch-controlled element for limiting the oscillatory movement of the said shaft and the horns, a brake connected with the said shaft to resist its movement, and the movement of the horns, and means for simultaneously releasing the said brake and the said latch.
18. In an apparatus of the class described the combination of an inclined track, an element adapted to engage a car on the track to control the movement thereof, a brake for resisting the movement of the said element, means comprising a latch for stopping the said element at a definite point in its path and means for simultaneously releasing the said brake and the said latch.
19. In an apparatus of the class described the combination of an inclined track, a pivotally mounted shaft mounted transversely of the track, horns on the shaft adapted to extend into the path of the wheel of a car on the track to control the movement thereof, means comprising a latch-controlled element for limiting the pivotal movement of the said shaft and the said horns in one direction, a brake connected with the shaft to resist this movement and the movement of the horns, and means for simultaneously releasing the said brake and the said latch.
20. In an apparatus of the class described the combination of an inclined track, a shaft extending transversely of the track, an element secured to the shaft and adapted to engage a car on the track to control the movement thereof, a brake connected to the said shaft at one end to resist the movement thereof and of the said element, means comprising a latch for stopping the movement of the said shaft and the said element in one direction, a second shaft parallel with the first shaft, means for operating the said second shaft, and means controlled by the movement of the said second shaft for simultaneously releasing the said brake and the said latch.
21. In an apparatus of the class described, the combination of an inclined track, an oscillatory shaft extending transversely of the track, horns on the said shaft adapted to extend into the path of a car on the track to control the movement thereof, a normally stationary element, an arm on the shaft adjacent the said normally stationary element, and spring buffers between the arm and the element to limit the movement of the arm relative to the element in both directions.
22. In an apparatus of the class described, the combination of an inclined track, an oscillatory shaft extending transversely of the track, horns on the said shaft adapted to extend into the path of a car on the track to control the movement thereof, a normally stationary element associated with the said

shaft, an arm on the shaft adjacent the said normally stationary element, spring buffers between the arm and the element to limit the movement of the arm relative to the element in both directions, and means for releasing the said shaft to permit its movement and the corresponding movement of the said shaft.

23. In an apparatus of the class described, the combination of an inclined track, an oscillatory shaft extending transversely of the track, horns on the said shaft adapted to extend into the path of a car on the track to control the movement thereof, a normally stationary element, an arm secured to the shaft adjacent the said element, a spring connection between the arm and the element tending to hold the shaft in position with the horns in the path of a car, and a spring buffer between the arm and the said element to limit the movement of the arm relative to the element in the direction opposite to the action of the said spring connection.

24. In a car dumping apparatus, the combination of a track comprising a sharply inclined section, a movable element adapted to engage a car in dumping position on the in-

clined section to first resist and then stop the movement thereof in one direction, the said element being movable along lines extending in the general direction of movement of the car from points in the path thereof to points outside of the said path, and a friction brake connected to the said movable element to control the movement thereof.

35

25. In a car dumping apparatus, the combination of a track comprising a sharply inclined section, an oscillatory element adapted to engage a car in dumping position on the inclined section, the said element being movable about its axis along lines extending from points in the path of the car to points outside of the said path in the general direction of movement of the car, and a friction brake connected with the said oscillatory element to control it and thereby first resist and then stop the movement of an engaged car.

40

In testimony whereof I affix my signature, in presence of two witnesses.
